UNITED STATES PATENT OFFICE.

AUGUST WULFF, OF NEW YORK, N. Y.

SHEET-METAL CAN.

SPECIFICATION forming part of Letters Patent No. 779,339, dated January 3, 1905.

Application filed March 23, 1904. Serial No. 199,523.

To all whom it may concern:

Be it known that I, AUGUST WULFF, a citizen of the United States, residing at the city of New York, in the borough of Brooklyn and State of New York, have invented certain new and useful Improvements in Sheet-Metal Cans, of which the following is a full, clear, and exact description.

This invention relates to tin cans or other metallic receptacles of the sort in which a cover is sealed on, the cover being detached by the act of opening the can and being thereafter usable like an ordinary cover for closing the can. In constructing cans of this kind it has been found difficult to form the can and cover so that after separation the latter may be easily slipped upon the former and made to fit securely, and although some attempts have been made to overcome this difficulty still such structures are open to many objections, among which may be mentioned the great fault that considerable space must always be left between the cover and the contents of the sealed can. Objection exists not only to the presence of a large body of air in the can, but also to the undesirable agitation which the contents often suffer in transportation owing to their not being closely confined and as well to the extra cost of material and of transportation and storage of the cans.

The object of my invention is to produce a can which before sealing can be filled almost or quite to the cover-plate, so that practically no room whatever may be wasted, no extra cost for material, transportation, or storage entailed, and little if any agitation of the contents in handling and transportation of the can incurred, while after separation the cover may fit readily and securely upon the can and without the necessity of first removing any of its contents.

In the accompanying drawings, Figure 1 is an elevation of one form of a can made in accordance with my improvements, a portion of the detachable strip being shown as torn away to illustrate the manner of opening the can by removing the strip. Fig. 2 is a sectional elevation of a sealed can. Fig. 3 is an elevation of an opened can, showing how the cover may be placed thereon after opening

the can. Fig. 4 is a section of the parts seen at Fig. 3.

In the several views like signs identify like parts.

The body 1 of the can is closed or sealed by 55 means of a cup-shaped reversible cover which comprises a cap or disk portion 2 and a cylindrical rim 3, whose edge is turned or rolled over a narrow flange 4, formed upon the edge of the can, as at 5, forming a tight joint 60 therewith. The portion of the metal of the can within which the cover is inclosed consists of a strip 6, which, although integral with the can, is detachable, the strip being defined by scores 7 and 8, cut in the can, the upper score 7 65 immediately adjoining the flange 4 and the lower score 8 being at the top of a neck 9, formed at the upper portion of the can-body. The strip may be torn off, so as to open the can and separate the cover therefrom, and the latter may then be turned over and used as an ordinary cover, as at Figs. 3 and 4, the neck 9 being of such diameter as to fit snugly within the cover-rim 3 and of such depth as to permit a firm and substantial engagement of said rim 70 therewith. When the strip 6 is torn off, a fragment of the can, consisting of the flange 4, is left within the rolled-over edge of the rim and serves to stiffen the latter, while the neck 9, being of cylindrical form and being 75 left with a clean upper edge by the tearing off of the strip, as seen at Figs. 1 and 4, fits readily within the cover, which, owing to the flaring form of its rolled-over edge, is readily slipped over said neck, said flaring portion 80 also affording a hold for enabling the cover to be lifted off when required and preferably being of somewhat greater diameter than the main body of the can, thus tending to protect the latter from injury. 85

It will be seen that the neck portion 9, over which the cover is to fit, is surmounted by a portion 6 of greater diameter, which incloses the cover, said portion 6 being detachable, whereby the cover may be lifted from the can 95 and turned over and replaced in its natural position upon said neck. This detachable or strip portion 6, it will be observed, flares outwardly and upwardly from the score 8, forming a seat within which the reversible cover 100

fits snugly, and the cap portion of the cover is thus brought close to that portion of the can - body that forms its upper edge when opened. From this construction it will be understood that the can before sealing may be filled almost or quite to the level of the score 8, little or no air thus being left between the contents and the cover-plate 2, which is a desideratum, while a great economy of room is effected by reason of the can being entirely filled, which is important not only because of the saving in cost of metal, which amounts to a great deal in articles of this kind, which are usually manufactured in large quantities, but also because of the reduction in cost of transportation and storage of the cans both before and after filling.

I am not aware of any prior can which can be filled almost or quite to the cover-plate and from which the cover can be removed by tearing off a detachable strip and then used as an ordinary cover without the removal of any of the contents from the can.

The cover-rim 3 is preferably cylindrical and the flaring strip of clipped form—that is, having a substantially cylindrical body and an interior flange at its lower edge—the cap portion or plate 2 of the cover thus being enabled to lie in close proximity to the junction of the detachable strip with the body of the can—that is, to the score 8. It is not essential in carrying out my invention that the strip 6 be formed integral with the body of the can, as illustrated, although that is the preferred form, and said strip may, if desired, be formed or provided with a tab projecting beyond the vertical seam of the can-body, as usual, to form a hold for a ripping key of ordinary construction.

Having described my invention, I claim—
 1. A tin can whose edge is formed with a flange, the can being sealed by a cup-shaped reversible cover having a rim which is turned over said edge, and the body of the can immediately below said cover being of such size as to be capable of fitting snugly within said cover, a strip fitting around said rim and joining said flange to said body, said strip being detachable from both said body and said flange.
 2. A tin can formed at its mouth with a de-

tachable integral strip which flares upwardly and outwardly from its junction with the body, and a reversible cover having a rim which fits within said strip and is secured thereto to seal the can, the can at the junction of the body with said strip being of such diameter that it may fit snugly within the rim of the detached cover.

3. A tin can closed by means of an inverted rimmed cover, the edge of the can having a narrow flange, the edge of the cover-rim being rolled over said flange, the can being formed with an integral detachable cupped strip immediately beneath the rolled rim of the cover, the cap portion of the cover fitting in the lower or cupped portion of the strip and lying in close proximity to the junction of the strip with the body of the can, and said body being formed at said junction with a neck of such diameter that it may fit snugly within the rim of the detached cover, and of such depth as to permit a firm and substantial engagement of said rim therewith.

4. A tin can formed with a flanged edge and with a detachable integral strip between the flange and the body of the can, said strip flaring upwardly and outwardly from its junction with the body, and a reversible cover having a rim which fits within said strip to about the full depth thereof and is rolled over said flange, the can at the junction of the body with said strip being of such diameter that it may fit snugly within the rim of the detached cover.

5. A tin can formed with a detachable integral strip of cylindrical form contracted at its lower portion, the metal of the can being scored at the junction of the can-body with said contracted portion, and a reversible cover having a cylindrical rim fitting snugly within said strip, the can at the junction of the body with the strip having cylindrical form and being of such diameter that it may fit snugly within the rim of the detached cover.

In witness whereof I subscribe my signature in presence of two witnesses.

AUGUST WULFF.
